(57) **CLAIM**

The ornamental design for a packaging container for battery, as shown and described.

DESCRIPTION

FIG. 1 is a front, bottom and left-side perspective view of a packaging container for battery showing my new design; FIG. 2 is a front, top and right-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged view of the area 9 indicated by the single dot-dash broken lines in FIG. 1; and,

FIG. 10 is an enlarged view of the area 10 indicated by the single dot-dash broken lines in FIG. 2.

The evenly-spaced broken lines depict portions of the packaging container for battery that form no part of the claimed design. The rectangle indicated by the single dot-dash broken lines shown in FIG. 1, FIG. 2, FIG. 9 and FIG. 10 illustrate the boundary of enlarged area of the design. The "9" and "10" indicia and splined curve indicated by the single dot-dash broken lines in FIG. 1, FIG. 2, FIG. 9 and FIG. 10 identify the enlarged area. None of the broken lines form any part of the claimed design.
